UNITED STATES PATENT OFFICE.

PERRY BROWN, OF CORAOPOLIS, PENNSYLVANIA.

DRAFT-RIGGING.

1,232,651.

Specification of Letters Patent. Patented July 10, 1917.

Application filed July 13, 1914. Serial No. 850,695.

To all whom it may concern:

Be it known that I, PERRY BROWN, a citizen of the United States of America, and a resident of Coraopolis, in the county of 5 Allegheny and State of Pennsylvania, have invented certain new and useful Improvements in Draft-Rigging, of which the following is a specification.

This invention relates to improvements in 10 draft riggings of that character in which followers are arranged between a pair of side bars located between the intermediate 15 sills of a car, springs or other cushioning devices being located between the followers to absorb the blows.

The invention consists in the construction and arrangement of parts hereinafter more fully described and set forth in the appended claims.

20 In the drawings accompanying and forming part hereof:

Figure 1 is a top plan view, with parts in section, of a draft rigging showing the preferable embodiment of my invention;

25 Fig. 2 is a longitudinal vertical section of the same;

Fig. 3 is a vertical central section taken on a line going through the springs;

30 Fig. 4 is a perspective view of one of the side bars detached;

Fig. 5 is a perspective view of the rear follower detached;

Fig. 6 is a perspective view of one of the intermediate sills, the front follower and 35 part of one of the side bars;

Fig. 7 is a longitudinal section of a modified form;

Figs. 8 and 9 are details of the modified form;

40 Fig. 10 is a perspective view of the bottom of a modified form of rear follower.

Referring now to the details of the drawings by numerals: 1 designates the ordinary end sill of a car and 2 and 3 the intermediate sills. The ordinary coupler or draw bar has its shank 4 passing through the end sills and between the intermediate sills, in the usual way, the said shank being supported by a carry-iron as 6 in Figs. 1 and 2.

50 The longitudinal sills are slotted slightly at the rear of the end sill, as indicated at 8 and 10. In the form shown in Figs. 1 and 2 a horizontal supporting bar 12 is employed which passes through the slots 8 and 55 10 of the intermediate sills 2 and 3 and also through a slot 14 in the shank 4 of the

draw bar. As will be seen in Fig. 1, the horizontal supporting bar 12 snugly fits the opening 14 in the draw bar shank but has play in each direction in the long slots 60 8 and 10 of the intermediate sills. Located between the intermediate sills, and just behind the draw bar shank is a front follower 16 between which and the rear follower 18 are interposed the usual springs 20. These 65 followers 16 and 18 are chambered as illustrated in Fig. 2 to receive the aforesaid springs 18 and the space between the chambered walls of the followers 16 and 18 is such that these walls will come together 70 to prevent the springs from being crowded beyond their capacity. As illustrated in Fig. 2, the springs are of different lengths, the lighter springs being longer than the heavier springs so as to take up the lighter 75 shocks and give increased travel while after a slight movement of the follower both springs come into play to absorb the heavier shocks. The rear follower abuts against a pair of heavy castings 24 and 26 which are 80 riveted to the intermediate sills 2 and 3 and have bolts 30 passing through them, the bolts also passing clear through the intermediate sills 2 and 3 so as to prevent any spreading of said sills. The front ends of 85 these castings 24 and 26 are hollowed out as shown at 32 and 34 as indicated in Fig. 1 for a purpose to be explained. Each of the followers 16 and 18 is formed of the shape shown in Fig. 5, that is to say, each follower 90 has a pair of lugs 40 at the upper end and a pair of lugs 42 at their lower ends, the lugs 42 of the rear follower being extended rearwardly as shown at 46 in Fig. 5. The lugs 40 and 42 of the followers are designed to 95 straddle or extend over a pair of side bars 50 and 52 which are generally of the shape shown in the perspective view in Fig 4. As there shown, the front end of each side bar is provided with a slot 54 with reinforced 100 walls through which passes the horizontal bar 12 hereinbefore referred to as passing through the opening 14 of the shank of the draw bar. The rear end of each side bar is provided with a hook shaped end designated 105 56. This hook shaped end may be of any desired shape, but I prefer that shown in the drawings. The rear sides of these hook shaped ends 56 are designed to fit into the recesses 32 and 34 hereinbefore referred to 110 as being formed in the front ends of the castings 24 and 26 and the hooks are de-

signed to hook into recesses 60 (see Fig. 5) formed in the rear follower 18. This hooked end serves the double purpose of drawing the rear follower forward on a "pull" and 5 also of preventing the side bars from being spread apart and it follows that if the bars 50 and 52 cannot spread the tendency of the sills to spread is greatly overcome. I have hereinbefore described the rear follower 10 as having projections 46. These are for the purpose of supporting the rigging in its proper position, as the projections 46 are designed to rest upon a carry-iron 62, illustrated in Figs. 2 and 4. Or, instead of 15 having the projections 46, the rear follower may be provided with a buttressed flange 63 (Fig. 10) which would rest upon the carry-iron 62. Any kind of cheek plate or abutments may be used on the inner faces 20 of the intermediate sills 2 and 3, but I prefer to employ an arrangement like that shown in the drawings comprising a casting designated by the numerals 64. This casting extends from the point designated 25 65 in Figs. 1 and 6 clear up to the end sill and its front is flanged as at 66 and riveted to both the end sill and to the intermediate sill. In the form shown in Figs. 1, 2 and 6, this abutment casting is slotted as indicated 30 at 67 for the movement of the horizontal bar 12.

The side bars also have lugs 53 which are normally the same distance from the abutment 65 as there is space between the followers, so that said lugs will contact at 65 at the same moment the springs are compressed to their capacity. Lugs 55 are also formed on the rear ends of the bars to contact with the castings 24 and 26.

40 In the modified form shown in Figs. 7, 8 and 9, I omit the slots 8 and 10 in the intermediate sills 2 and 3, and employ only slots 70 formed in the abutment castings 62. These abutment castings are formed with 45 openings 72 which enter the slots 70, and the horizontal bar 74 instead of being long enough to pass through the intermediate sills as at 12 in Fig. 1, is only long enough to bridge the space between the intermediate 50 sills. In assembling the parts of the modified form, the rigging is first placed in position and then the draw bar with the horizontal bar 66 passing through its shank is inserted upward from beneath the car 55 through the opening 72 of the abutment castings when the carry-iron is placed under the shank of the draw bar in order to support the same. When this carry-iron is in position the horizontal bar 74 will be in the 60 position shown in Figs. 8 and 9 so that it may be moved either forwardly or rearwardly within the slot 70 the rear end of the rigging being supported by the lugs 46 projecting from the rear follower over the 65 carry-iron 62 as hereinbefore described.

In operation, whether in the preferred form or in the modified form, upon an "impact," the draw bar shoves the front follower 16 to the rear compressing the springs between the two followers 16 and 18, the thrust being received by the rear follower abutting against the heavy castings 24 and 26. On a "pull," the draw bar shank pulling upon the horizontal bar 12, in the preferred form or the bar 74 of the modified form, draw the side bars 50 and 52 forwardly and as the rear ends of these side bars are hooked into the rear follower, said rear follower is also drawn forward to compress the springs between it and the front follower 16, the front follower being held from forward movement by means of the rear ends 65 of the abutment casting 63.

From the foregoing and the accompanying drawings, it will be seen that I have invented a draft rigging in which the intermediate sills are securely connected together by means of the heavy castings, 24 and 26 and the bolts 30, so as to prevent spreading of the sills, but the side bars 50 and 52 are provided with projections which enter recesses in the castings 24 and 26 secured to the intermediate sills so that upon an "impact" these parts will also tend to prevent any spreading of the sills. Furthermore, as the side bars are provided with members as the hooks 56 to co-act with the rear sides of the rear followers, it will be noticed that these rear followers do not need any separate connection as for example, a horizontal bar, bolts or equivalent means, to connect the rear follower with said side bars.

It will be obvious that modifications may be made without departing from the spirit of my invention, the scope of which is set forth in the appended claims.

What I claim as my invention is:

1. In draft rigging and in combination with the sills and draw bar, a pair of side bars, front and rear followers, and a casting secured to the sills and receiving the blow from said rear follower, said side bars and said casting having complementary projections and recesses co-acting to prevent spreading upon an "impact."

2. In draft rigging and in combination with the sills and draw bar, a pair of side bars, front and rear followers, a pair of castings secured to said sills and having recesses therein, said side bars having projections fitting in said recesses upon an impact and thereby preventing spreading.

3. In draft rigging and in combination with the sills and draw bar, a pair of side bars, front and rear followers, a pair of castings secured to said sills and having recesses therein, said side bars having projections fitting in said recesses upon an impact and thereby preventing spreading, and a

bolt passing through said castings and through said sills.

4. In draft rigging and in combination with the sills and draw bar, a pair of side bars connected with said draw bar, front and rear followers each having lugs projecting over and under said side bars, abutments on the sills co-acting with the lugs projecting from said followers, the rear ends of 10 said side bars having hooks co-acting with the rear follower, said rear follower having a horizontally projecting member and a carry-iron connected with the sills and supporting said horizontally projecting member.
- 15 5. In draft rigging and in combination

with the sills and draw bar, a pair of side bars, followers between said bars arranged to abut to prevent the springs from crowding, abutments carried by the sills co-acting 20 with said followers, and a lug on each side bar located to contact with the abutment when the followers abut against each other under outward movement or draft on the draw bar.

25 In testimony whereof I affix my signature in presence of two witnesses.

PERRY BROWN.
